UNITED STATES PATENT OFFICE.

ALVA C. RICE, OF WORCESTER, MASSACHUSETTS; ASSIGNOR TO VELLUMOID PAPER COMPANY, OF WORCESTER, MASSACHUSETTS, A CORPORATION OF WEST VIRGINIA.

TREATING-TANK FOR PAPER.

No. 888,741.

Specification of Letters Patent.

Patented May 26, 1908.

Application filed March 8, 1907. Serial No. 361,226.

To all whom it may concern:

Be it known that I, ALVA C. RICE, a citizen of the United States of America, residing at Worcester, in the county of Worcester and State of Massachusetts, have invented certain new and useful Treating-Tanks for Paper, of which the following is a specification.

My invention relates to improvements in tanks and their appurtenances used in treating paper and particularly in the manufacture of what is known as vellumoid paper, the same being that described and claimed in United States Letters Patent numbered 804,808, and dated November 14th, 1905, and consists of a certain peculiar construction and arrangement of tanks proper and of special means and mechanisms for actuating and handling the paper while passing through the tanks, all as hereinafter set forth.

The objects of my invention are, first, to produce mechanical means for expeditiously and economically treating paper of different grades and weights to toughen and strengthen the same and to render it impervious to water, grease and acid; second, to afford adjustable means for properly guiding the paper in its passage through the treating tanks; third, to furnish the press-rolls with an adjustable weight or pressure device; fourth, to provide a delicate adjustment for the actuating mechanism for the paper whereby an even and uniform tension can be maintained; and, fifth, to embody my improvements in a practicable, efficient and comparatively compact form to the end that a better and cheaper product is produced than heretofore. I attain these objects by the means and mechanism illustrated in the accompanying drawings, in which—

Figs. 1 and 1^a are a plan view of the two tanks which I prefer to employ with some of their auxiliary and associated devices and members, portions of Fig. 1^a being broken out to make room for the view below; Figs. 2 and 2^a are a longitudinal vertical section through the tanks and appurtenances, the course of the paper being here indicated; Fig. 3 is an enlarged end view of one of the adjustable guide rollers and of the mechanism therefor; Fig. 4, a sectional detail of said mechanism, taken on lines 4—4, looking in the direction of the arrow 3, in Fig. 3, only the connected end portions of the roller and of the shaft and tube above being shown; Fig. 5,

an enlarged side elevation of the adjustable weight or pressure regulator used with each set of press-rolls; Fig. 6, a vertical section taken on lines 6—6, in Fig. 7, and; Fig. 7, an enlarged elevation of one of the belt shippers or adjusters provided to equalize the strain on the paper and insure a uniform pull thereon.

Similar figures refer to similar parts throughout the several views.

The arrows in the first four views indicate the directions of moving members.

In carrying my invention into effect I make use of two tanks placed one ahead of the other, for reasons which will be clearly apparent hereinafter, the first of these tanks being for a glutinous solution and the second for a formaldehyde solution, but it will be readily understood that the tanks and their appurtenances might be employed separately under some conditions.

The first or left-hand tank, that for the glutinous solution or liquid glue, comprises in this instance a suitably supported wooden receptacle 10 and two metallic basins 11 and 12 each provided with a flange 13 arranged to support its basin from the upper edge of said receptacle, the flange of the basin 11 resting directly on such edge and the flange of the basin 12 resting directly on the other flange, as best shown in Fig. 4. The upper basin 12 covers all of the basin 11 below except for a short distance at the left-hand or front end. Extending across and above the basin 12 at the front end is a perforated pipe 14 through which the liquid glue is admitted to said basin, such pipe having connections which lead to the source of supply of said glue.

Behind the pipe 14 is a second perforated pipe 15, through which steam or hot water may be injected into the glue basin. In the bottom of the basin 11 is a series of perforated steam-pipes 16 connected with a suitable source of supply. The glue in the basin 12 is kept at the desired temperature by means of hot water in the water basin 11 below, the water being maintained at the proper heat by steam from the pipes 16 in said basin 11. This manner of providing moist heat for the glue, below and around the same, is a very valuable feature of my invention, since in no other way can so good results be produced, that is to say, an improved paper is the outcome of treatment under the conditions provided by

my tank. In practice, during the operation of the mechanism, I prefer to pump a quantity of the solution into the basin 12 through the pipe 14, in excess of the amount 5 actually required for the paper, and I provide an overflow pipe 17 at the back end to take care of this excess; in this way I keep the whole of the solution in said basin in motion and at a substantially constant level.

10 It is thus possible to have a solution of the same consistency throughout at all times and to get more uniform and better results with the paper.

At the front end of the glue tank frame or 15 support are two pairs of forwardly-projecting arms 18 and 19 notched at 20 for paper roll spindles, one such spindle 21 being shown in position in the notches in the lower arms supporting a paper roll 22 between said 20 arms. A guide roller 23, over which the paper 24 from the roll 22 first passes, is mounted above the front edge of the receptacle 10 in any suitable manner.

One or more rollers 25 and 26 are provided 25 for this tank, the former being so arranged as to be adjusted longitudinally of the tank and also to be adjusted vertically by being swung up and down on their supporting members as will presently be explained. 30 The rollers 26 are journaled in ordinary swivel bearings or supports 27 located wherever desired at the sides of the receptacle 10. The object in having swivel bearings for the rollers 26 is to enable them to be easily adjusted from either end to suit the paper which passes over them so as to have no tendency to cause the paper to draw more on one side than on the other. At the back end of the tank on each side is a bifurcated standard 28 and squeeze-rolls or press-rolls 29 and 40 30 are mounted between these standards, which rolls operate in the manner described in detail hereinafter.

The second or right-hand tank, that for 45 the formaldehyde solution, is shorter than the other and consists of a wooden receptacle 31, supported in a similar manner to the receptacle 10, and a single metallic basin 32 supported by a flange 13 from the upper edge 50 of said receptacle 31. One or more rollers 25 are provided for the formaldehyde tank, and it has standards 28 and press-rolls 29 and 30 at the rear end like the glue tank. The formaldehyde is introduced into the basin 32 in any suitable manner. An overflow tube 33 is provided at the back end of the formaldehyde tank to take care of any excess of formaldehyde that may accumulate in the basin 32. Adjacent ends of the two 55 tanks are connected by a frame 34 upon which four guide rollers 35 are mounted, two on the side pieces at the top and two on the uprights.

Journalized in suitable bearings fastened on 60 65 the framework which supports each tank are

shafts 36 and 37 upon which are mounted cone-pulleys 38 arranged in the usual manner with the large end of each adjacent the small end of the next. A belt 39 connects the cone-pulleys 38 on the first pair of shafts 36 70 and 37, and a similar belt connects the cone-pulleys on the next pair of shafts 36 and 37. There is a pinion 40 on one end of each shaft 37 which meshes with a gear 41 on a shaft 42 suitably mounted beneath the tank with 75 which it is associated. On the same shaft 42 with the gear 41 is a pinion 43 which meshes with a gear 44 on the shaft 45 of each press-roll 29. The press-roll shafts 45 are journaled in bearings 46 in the standards 28. 80 Each of the shafts 47 of the upper press-rolls 30 has each end journaled in a bearing 48 slidingly mounted in the vertical slot 49 in each standard 28 above the associated bearing 46. The upper and under press-rolls are 85 in contact with each other so that the upper rolls are driven from the under ones. On adjacent ends of the shafts 36 are two pulleys 50 connected by a belt 51, and on one of these shafts, the second in this case, is a pulley 52 90 which receives power from the main shaft. It will now be seen that power is transmitted from the pulley 52 to the press-rolls, which actuate the paper and at the same time squeeze out or wring out the surplus glue and 95 formaldehyde, through the medium of the pulleys 50 and belt 51, shafts 36, cone-pulleys 38 and belts 39, shafts 37, pinions 40, gears 41 and pinions 43 on the shafts 41, and gears 44 on the shafts 45.

I provide a pressure regulator to act upon each upper press-roll 30 and to bear the same down onto the associated lower press-roll 29 with a degree of pressure which may be varied, which I will next describe. On the top 105 or cap plate 53 of each standard 28 is a vertical lug 54 slotted at the upper terminal to receive a rack 55 which is pivoted at 56 to said lug. The four racks 55 thus mounted are parallel with the sides of the tanks below and the two in each pair are parallel with each other. Pivoted at 57 to each rack 55 behind the pivot 56 is a slotted stirrup 58 having a spindle 59 extending downward through the cap plate 53 into engagement with the 110 bearing 48 below. A slot 60 is provided in the rack for the pivot pin 57 so as to permit said rack to rock on its pivot 56 and actuate the stirrup 58 and its spindle without moving them out of the perpendicular. A weight or 115 heavy roller 61 having cogs or teeth 62 at each end to mesh with the rack teeth is mounted on each pair of racks 55. At one end of each roller is an angular extension 63 adapted to receive a key or crank to facilitate 120 revolving said roller and thus rolling it along on the racks. The arrangement of these parts is such that, when either roller 61 is moved forward on its racks 55 in front of their pivotal points 56, it acts to raise the asso- 125 130

ciated press-roll 30 from the press-roll below through the medium of said racks, which are now tilted up behind, and the connecting stirrups 58, and when moved behind such points said roller acts by forcing down the rear terminals of the racks and through the same medium to depress said press-roll 30 and to force it against the companion press-roll with a pressure that increases with the distance between the regulator roller and said pivotal points. By this means it is not only possible to open and close the press-rolls with ease, but also to adjust or regulate the pressure on the paper between such rolls with great nicety, such regulation being required to accommodate papers of different grades and weights.

It is imperative in mechanism of this kind to have a delicate adjustment for the paper-actuating mechanism in order not to tear or unduly strain the paper, and for such purpose an adjuster is provided for each belt 39. Said adjuster, which I will now proceed to describe, consists essentially of two pairs of vertical idlers 64 supported from a sleeve 65 mounted on a screw 66 journaled in two of the tank supports or legs 67. The upper reach of the associated belt 39 passes between the upper pair of idlers and the lower reach of such belt passes between the lower pair of idlers. The screw 66 has a hand-wheel 68 on one end and is revoluble, but it is held in place against endwise movement by collars 69—69 and 70 and a nut 71 thereon, said collars 69 being located against the inside faces of the legs 67. The hand-wheel 68 is outside of one of the legs 67 and the collar 70 and nut 71 are outside of the opposite leg. Extending above and below the sleeve 65 are four arms 72 having longitudinally screw-threaded passages 73 therein. A spindle 74 is provided for each of the lower arms 72 and a spindle 75 for each of the upper arms 72, such spindles having screw-threaded inner terminals to enter the passages 73. The idlers 64 are open at the bottom and have interal hubs 76. Each spindle 74 is provided with a shoulder 77, which forms a bearing for the associated idler, and with a screw-threaded extension 78 at the base for a nut 79. Each lower hub 76 is received into a collar 80 which is slipped onto the spindle extension 78 and held rigidly in place by the nut 79. A flange 81 in this collar supports the parts above on cross-pieces or guides 82—82 extending between the legs 67 and spaced apart to receive between them a projection 83 which is the part of the collar against which the nut 79 bears. The idler is free to revolve on the shoulder 77 and in the collar 80. Each spindle 75 is provided with a shoulder 84 and a collar 85 for the mounting of each upper idler, said collar being held in place between said shoulder and the top of the supporting arm 72. It is understood, of

course, that both the collars 80 and 85 are closed at the base save for the openings therein for the extension 78 and the inner terminal of the spindle 75. A screw-threaded extension 86 at the top of the spindle 75 receives a small flanged collar 87, which prevents the idler from working upward, and a nut 88, the latter securing said collar in position. The nut 88 is received between a pair of angle-irons or guides 89 fastened on the underside of the receptacle 10, or of the receptacle 31, as the case may be, and extending above and parallel with the guides 82. The two pairs of guides help to sustain the members which serve as supports for the idlers and prevent such members from turning on the screw 66.

From the above it will be readily seen that, by turning the hand-wheel 68, the screw 66 causes the sleeve 65 to be actuated in one direction or the other, according to the direction in which such wheel is turning, thus moving the idlers 64, through the medium of the intervening mechanism, and adjusting the belt 39 on the cone-pulleys 38 so as to drive the associated press-rolls 29 and 30 either faster or slower. By this means both sets of press-rolls can be easily and quickly brought into exact correspondence and the pull on the paper during its passage through the tanks made uniform.

Racks 90 are provided on the upper edges of the receptacles 10 and 31 upon which are mounted for adjustment longitudinally of the tanks the supports for the rollers 25. These supports consist of bearing boxes 91 and 92 on opposite sides of the tanks for shafts 93 having pinions 94 tight thereon to mesh with the racks 90, the boxes 91 on the working side of the tanks differing from the others only in that they are provided with upright flanges 95 having slots therein concentric with said shafts. One of the aforesaid slots is best shown as 96 in Fig. 3. Loosely mounted on each shaft 93, inside of the boxes 91 and 92, are two hangers 97 and 98, and said hangers are connected by a tube 99 which incloses said shaft between the hanger hubs and has its ends in threaded engagement with said hubs, as will be seen upon referring to Fig. 4. The tube 99 is threaded at the ends to receive lock-nuts 100 and to screw into the hubs of the hangers 97, said lock-nuts being set up tight against the adjacent ends of said hubs to securely fasten the hangers and tube together. Projecting from the hanger 97 behind each flange 95 is a handle 101, by means of which said hanger with the hanger 98 connected therewith by the tube 99 can be rotated on the shaft 93 upon which the parts are mounted, and in threaded engagement with which after passing through the slot 96 in said flange is a hand-screw 102. The hand-screw 102 is adapted to lock and release the handle 101 to and from the con-

tiguous flange 95, and to be moved to any point within the slot 96 provided therefor. Now, therefore, since the trunnions 103 of each roller 25 are journaled in the bases of the supporting hangers 97 and 98 for such roller, as shown in Fig. 4, it is apparent that, to adjust said roller at the proper height, it is only necessary to loosen the attendant hand-screw 102, move the handle 101 in whichever direction and to whatever extent may be required to bring about the desired adjustment, and then tighten said hand-screw again. This can be accomplished without disturbing the supporting shaft 93. On the end of each shaft 93 which is on the working side of the tanks is a crank 104 by means of which said shaft is revolved to change the position of the associated roller 25 longitudinally relative to the tank in which it is located, the movement being effected through the medium of the pinions 94 and the racks 90 and the direction depending upon the direction of rotation given said crank. The adjustment longitudinally of the roller 25 does not affect its elevation or, in other words, change the horizontal plane of its axis, because the construction and arrangement is such that the reciprocating mechanism and the swinging mechanism for said roller are operated entirely independently of each other.

It is to be remembered that whatever twin parts are used with the tanks said parts are duplicates of each other in all essential particulars both in construction and operation.

Although the complete operation of the tank mechanism will be pretty generally understood from the foregoing explanation, it may be stated briefly to be as follows, assuming that the tanks have been properly charged, the pipes 16 heated, and all is in readiness: First the rollers 25 (and 26 when used) are adjusted in whatever manner and to whatever extent may be thought to be necessary, and then the paper 24, if a very heavy paper, is led from the supply-roll 22 and the roller 23 beneath the first roller 25 into floating contact with the liquid glue in the basin 12, thence over the second roller 25 to the third roller 25, in floating contact with the glue all the time, and then below the surface of the solution to the first press-roll 29. The paper next passes upward, between and over the first set of press-rolls, the roller 61 being so manipulated as to separate the two press-rolls by lifting the upper away from the lower for the passage of the paper and again manipulated to depress the upper press-roll and force it against the paper on the under press-roll with whatever degree of pressure may be required. From the upper press-roll the paper passes back and forth and back again over the rollers 35, as shown in Fig. 2*. From the upper rear roller 35 the paper passes or is lead to the first roller

25 in the formaldehyde basin 32 and from that to the second roller 25, being submerged in the liquid in said basin while being led beneath said rollers 25 and from the second of these rollers to the second press-roll 29. The paper passes through the second set of press-rolls in the same way that it did through the first set, and is led from said second press-rolls to a drier (not shown). When first introducing the paper into the mechanism both sets of press-rolls should be left open until the paper has been correctly adjusted. The power is now turned on and the paper is drawn through the liquid glue and the formaldehyde solution in succession, the press-rolls removing the surplus of each as the paper passes between them. Any required additional adjustment of any one of the rollers 25 is effected by either turning the crank 104 or changing the position of the handle 101 or both, and any unevenness in the pull on the paper is corrected by manipulating one or both of the hand-wheels 68.

A lighter paper calls for less exposure to the solution in the first tank and generally for less exposure to the solution in the second tank also; the exposure to the solution in either tank can be shortened or lessened in various ways, such as, for example, by decreasing the distances between the rollers 25, by decreasing the distance between the last roller 25 in either tank and the adjacent press-roll, by decreasing the depth to which the paper is submerged, and by using fewer rollers 25—any and all of these expedients may be resorted to in order to secure the desired results. From the above it is clear what method would be pursued in preparing to treat heavy paper after treating a light or thin paper. Some of the lighter paper is led over one or both of the rollers 26 before being brought into contact with the glue and the first roller 25 is not used therefor, and such paper does not usually pass over all of the rollers 35 since a less amount of exposure to the air, between the tanks or between the baths therein or exposures thereto, is sufficient. So far as my invention is concerned it is immaterial how many or few of the different kinds of guide rollers are in actual use at any given time or what number is provided so long as there are enough to insure the proper working of the tank mechanism.

It will be clearly understood that the paper while being treated passes into, through and out of the two solutions in a continuously moving unbroken strip.

It is evident that many changes in the construction and arrangement, particularly in the latter, of the different parts and members may be made without departing from the nature of my invention.

What I claim as my invention, and desire to secure by Letters Patent, is—

1. The combination, in a treating tank for

- paper, of a suitably supported basin for water, means to heat the interior of said basin, a second basin suitably supported within the first and covering the same except 5 at one end, and one or more perforated pipes extending across said second basin adjacent to the open end of said first basin.
2. The combination, in a treating tank for paper, of a suitably supported basin for 10 water, heating pipes in said basin, a second basin suitably supported within the first and covering the same except at one end, and a supply pipe for said heating pipes entering the open end of said first basin.
- 15 3. The combination, in a treating tank for paper, with the tank, of a guide roller mounted thereon, and revolute means for adjusting said roller longitudinally of the tank.
4. The combination, in a treating tank for 20 paper, with the tank, of a guide roller mounted thereon, revolute means for adjusting said roller longitudinally of the tank, and oscillatory means for adjusting the roller at different levels.
- 25 5. The combination, in a treating tank for paper, with a tank provided with racks on its upper edges at the sides, of bearing-boxes mounted on such edges, a shaft journaled in such boxes and provided with pinions meshing with said racks, hangers carried by said shaft, a guide roller supported by said hangers, and means to revolve the shaft.
6. The combination in a treating tank for 30 paper, with the tank, of bearings for a shaft suitably mounted on said tank, one of such bearings having a flange, a shaft supported by said bearings, connected hangers carried by said shaft and adapted to be oscillated thereon, a guide roller supported by said 35 hangers, and means for adjusting the hangers to locate said roller at different levels, such means comprising a hand-screw adapted to engage said flange and the adjacent hanger.
- 40 45 7. The combination, in a treating tank for paper, with a tank provided with racks on its upper edges at the sides, of bearing-boxes mounted on such edges, a shaft journaled in such boxes and provided with pinions meshing with said racks, means to revolve said shaft, connected hangers loose on the shaft, a guide roller supported by said hangers, and means for adjusting the hangers to locate 50 said roller at different levels.
- 55 8. The combination, in a treating tank for paper, with the tank, and press-rolls to actuate and squeeze the paper being treated, of 60 sliding bearings for the upper press-roll, pivotally mounted rocking supporting members extending beyond their axes on both sides, a
- rolling weight arranged to travel on said supporting members and capable of tilting them at either end according to the position of such weight thereon, and connections between said sliding bearings and such rocking supports.
9. The combination, in a treating tank for paper, with the tank, and press-rolls to actuate and squeeze the paper being treated, of 65 sliding bearings for the upper press-roll, standards for such bearings, racks pivotally connected with such standards, connections between said racks and said sliding bearings, and a rolling weight on the racks, such weight being serrated to engage the rack serrations.
10. The combination, with a treating tank, for paper, the press-rolls associated with said tank, and driving mechanism for such rolls, consisting in part of cone-pulleys and a connecting belt, of a screw suitably mounted between said pulleys and between the reaches of said belt, a collar mounted on and adapted to be actuated by said screw, mountings carried by said collar, guides above and below 70 said mountings arranged to receive the ends of the latter and to prevent the collar from rotating, without interfering with its longitudinal movement, and idlers on the mountings both sides of the belt.
11. The combination, with a treating tank, for paper, the press-rolls associated with said tank, and driving mechanism, for such rolls, consisting in part of cone-pulleys and a connecting belt, of a screw suitably mounted between 75 said pulleys and between the reaches of said belt, a collar mounted on and adapted to be actuated by said screw, mountings carried by said collar, the lower mountings being provided with supporting flanges, guides 80 above and below said mountings arranged to receive the ends of the latter and to prevent the collar from rotating, without interfering with its longitudinal movement, said flanges 85 resting on the lower guides, and idlers on the mountings both sides of the belt.
12. The combination, of a treating tank comprising a suitable support and two basins thereon arranged one within the other, the lower or under basin being for water, perforated steam pipes in said lower or under basin beneath the bottom of the other basin, a second treating tank comprising a suitable support and a basin thereon, and means to 90 actuate paper into and out of both of said tanks.
